UNITED STATES PATENT OFFICE

LOUIS PHILIPPE PETIT, OF GRANBY, QUEBEC, CANADA

DIRECTION INDICATOR FOR VEHICLES

Application filed August 1, 1930. Serial No. 472,264.

The present invention pertains to a novel direction indicator for vehicles, particularly motor vehicles.

The principal object of the invention is to provide a device of this character which may be mounted at the sides of the vehicle and operated in accordance with the direction in which the vehicle is about to turn. The device comprises essentially an elongated slidable member, preferably pneumatically operated, carrying another member movable therewith as well as relatively thereto. The relative movement occurs at the end of the contemporaneous movement as is utilized to 10 actuate pivoted indicating arms carried by the movable members.

The invention is fully disclosed by way of example in the following description and in the accompanying drawings in which

20 Figure 1 is a longitudinal section of the device in idle position;

Figure 2 is a similar section of the device in semi-operative position;

Figure 3 is a detail elevation of the device 25 in operative position;

Figures 4 and 5 are detail longitudinal sections;

Figure 6 is a similar detail section in a different but parallel plane;

30 Figure 7 is a detail longitudinal section at right angles to Figure 6;

Figure 8 is a section on the line 8—8 of Figure 6;

Figure 9 is a longitudinal section of the 35 valve; and

Figure 10 is a section on the line 10—10 of Figure 3.

Reference to these views will now be made 40 by use of like characters which are employed to designate corresponding parts throughout.

With reference first to Figures 1, 2, 3 and 45 it will be seen that the device comprises two tubes 1 and 2, preferably of equal length, joined together in alinement by being threaded on a plug 3. A piston 4 is slidably mounted in the tube 2 and is carried on a piston rod 5 passing through the plug 3.

The latter is fitted with a packing nut 6 50 surrounding the rod 5 to prevent leakage

through the plug, as shown more clearly in Figure 5.

The rod 5 is connected to the indicating members by means of linkage consisting of parallel strips or slats 7 between which is 55 slidably mounted an intermediate guide strip 8. The member 8 is of the same length as the tube 1 while the strips 7 are shorter, as may be seen by the extremities 7' of the latter shown in Figure 2; and the guide 8 is 60 secured to the strips 7 by rivets 9.

The guide 8 has a frame-like inner end 10 and is further slotted as at 11 throughout its entire length. The end 10 is joined to the piston rod 5 by pins 12 as clearly shown in Figures 6 and 7. In the slot 11 is slidably mounted a link 13 having a head 14 disposed in the frame-like end 10 of the member 8. A pin 15 held rigidly in the head 14 is adapted to move in slots 16 in the lateral strips 7 as will presently appear. A spring 17 is received in the end 10 and bears against said end and the head 14 and ends of members 7, as shown in Figures 6 and 7.

The outer end of the guide 8 has a pair of 75 indicating arms 18 pivoted thereto on pins 19 and adapted to swing outwardly in opposite directions as shown by the arrows in Figure 2. When turned inwardly, they engage the ends 7' of the members 7 as also shown in 80 this figure. A pin 20 fixed in the link 13 is received in notches or slots 21 in the pivoted ends of the arms 18.

For controlling the operation of the device, there is provided a two-way valve of the type 85 shown in Figure 9. A cylinder 22 has a pressure intake port 23 and two outlet ports 24 and 25 with which the port 23 may be selectively connected. A rod 26 having an exterior operating handle 27 is slidably mounted in the cylinder and carries pistons 28 and 29 also slidable in the cylinder. The pistons are so spaced as to obstruct the intake port 23 from either of the outlet ports 24 and 25 90 while the other outlet port is in communication with the intake port. A spring 29' between the closed end of the cylinder and the piston 28 normally holds the piston rod 26 in the position connecting the ports 23 and 100

25. The ends of the cylinder are formed with vents 30 and 31.

The tube 2 has two lines 32 and 33 connected thereto, respectively behind and in advance of the piston 4. These tubes are connected respectively to the ports 24 and 25, so that the piston 4 is normally in the retracted position shown in Figure 1. When, however, the pistons 28 and 29 are shifted to 10 connect the intake port 23 to the port 24, pressure enters behind the piston 4 and advances the parts to the position shown in Figure 2. It will be understood that suction may be used as well as pressure, and the connections interchanged accordingly.

On application of pressure or suction to the device by the means already described, all parts within the tube 1 will be extruded therefrom uniformly by movement of the rod 5, to the position shown in Figure 2, until the pin 15 engages the outer end wall of the cylinder 1 as shown in Figures 4, 6 and 7. The link 13 is thus held against further movement, but the lateral members 7 are free to move the length of the slots 16 as may be seen by reference to Figure 7. Hence, further movement of the piston rod 5 actuates the members 7 in this manner through the spring 17. It will be recalled that the pin 20 is fixed relatively to the link 13, and consequently the continued outward movement of the lateral members 8 carries the pivot points 19 outwardly and swings the arms 18 to the position shown in Figure 3.

25. Two devices of the character described are mounted on the vehicle, one at each side. A contemplated turn of the vehicle in either direction is indicated by operating the device on the corresponding side.

40. Although a specific embodiment of the invention has been illustrated and described, it will be understood that various alterations in the details of construction may be made without departing from the scope of the invention as indicated by the appended claims.

45. What I claim is:—

1. A direction indicator for motor vehicles comprising a housing, an elongated member slidable through one end thereof, a link member movable with said elongated member and adapted for movement relatively thereto, an indicating arm pivoted to one of said members and having a connection with the other member, whereby to be swung by relative movement of said members, a slidable rod for actuating said members, and spring connection between said rod and one of said members, and a slot-and-pin connection between said members for permitting said relative movement therebetween.

60. 2. A direction indicator for motor vehicles comprising a housing, an elongated member slidable through one end thereof, a link member movable with said elongated member and adapted for movement relatively thereto, an

indicating member pivoted to said elongated member and having a connection with said link member, whereby to be swung by relative movement of said members, a slidable rod for actuating said members, a spring connection between said rod and link member, and a slot-and-pin connection between said members for permitting said relative movement therebetween.

65. In witness whereof I have hereunto set my hand.

LOUIS PHILIPPE PETIT.
